Attorney

UNITED STATES PATENT OFFICE

FRANCISQUE DAMON, OF LYON, FRANCE

VARICOSE STOCKING

Application filed November 11, 1928, Serial No. 406,420, and in France November 18, 1928.

The present invention relates to a knitted stocking for varicose veins of the type comprising an opening for the passage of the heel, formed during the knitting and surrounded with a zone of double thickness of fabric.

The stocking according to the invention is characterized in that the portion of double thickness of the heel has in the free state the form of a quarter of a sphere or of an ellipsoid and in particular is bounded by two rectangular planes.

The invention relates to the method of manufacture of the above stocking, characterized in that the double portion forming the heel is obtained by sewing along substantially rectangular faces of two bands which are separately knitted by the simultaneous working of the needle banks of the machine.

20 The annexed drawings will enable the above explanations to be better understood:

Fig. 1 shows on a small scale a stocking according to the invention, placed in position on the leg.

25 Fig. 2 is a side view on an enlarged scale of the part of the stocking adjacent the heel and is shown foot upwards, as it would be on the knitting machine.

Fig. 3 is a view of the back surface of the 30 stocking before sewing the bands together.

Fig. 4 is a view in perspective of the stocking after the bands are sewed together.

Fig. 5 is a section taken on line V—V of Fig. 3.

35 The stocking is knitted on a rectilinear machine with two needle banks of any known type, adapted to form a tubular web to which a tapering shape is given by means of suitable reductions. It will be assumed, for the sake of clearness that the front needle bank

40 knits the front face 1 of the stocking (Figs. 1 and 2), the back bank knitting the back face 2. The knitting is effected in the direction of the arrow 3. The line A—B represents the boundary of the two faces 1 and 2, that is to say the line of stitches formed by the outermost needles of each bank.

45 When the point B is reached, the work is stopped. The stitches are removed from the needles of the front bank and are mounted

on a comb. The line of stitches thus arrested by the comb is shown by the line B—C.

The work is then resumed with both needle banks, but with only half the number of the needles, all those situated on one side of the axis being rendered inoperative. At the first stroke of the carriage one connects the stitches of the two needle banks which will give the line B—D (Figs. 2 and 3). A tubular band of knitting is thus formed to which, by means of suitable reductions, the shape B D F E will be given as clearly shown by Fig. 3.

50 At E F the knitting is stopped and the needles which carry it are rendered inoperative and the needles previously rendered inoperative are again brought into action, so as to knit, on the other half of the back face, a second tubular band D F' E' B', symmetrical with D F E B (Fig. 3).

55 Then the sides DG and DG', FE and FE' are respectively sewn together. The stocking then has the appearance shown in Fig. 4, the portion of doubled fabric forming to some extent a quarter of an ellipsoid with cap removed. The front face 1 is still held on the 60 comb 4.

65 The stitches of the front face 1 are then remounted on the front bank of needles and the meshes of the selvedge B E E' B' on the back bank. The selvedge B E E' B' being greater than the edge B C B', in order to put an equal number of stitches of the two needle-banks some of the extreme stitches of the selvedge B, E, E', B' must be placed on the front needle-bank; that is to say the 70 stitches B, H (Fig. 2) and the stitches B', H' placed on the other side with respect to the plane of the figure).

75 In recommencing the work in the usual fashion the foot of the stocking is formed by suitable reductions. The limit of the working zones of the banks of needles is the line H, J. By the above method a stocking of elastic material is very simply produced and 80 which, contrary to known stockings, takes the form of the foot without considerable deformation being required.

85 In practice, to connect together the two thicknesses constituting the tubular bands 100

B, E, F, G, D, or B', E', F', G', D common lines of stitches 5 are formed.

I claim:

1. A method of manufacturing a stocking of the kind described on a rectilinear knitting machine having two banks of needles, comprising the following steps: first, to stop the work on the front face of the stocking when the heel portion is reached; second, to knit with both needle banks two double-thickness bands with reductions on their interior edges; third, to sew together the upper edges of said bands; fourth, to resume the work on the front face of the stocking and, at the same time, on the exterior edges of said bands.

2. A method as claimed in claim 1, wherein the double-thickness bands are knitted separately and in succession, their interior edges being sewn together for a limited length starting from the beginning of said bands.

In testimony thereof I affix my signature.
FRANCISQUE DAMON.
